UNITED STATES PATENT OFFICE

HARRY R. PRIEST, OF LOUDONVILLE, OHIO

SHAVING KIT

Application filed December 15, 1930. Serial No. 502,481.

This invention relates to shaving kits and has for an object to provide a case for the shaving brush, the base of the brush being provided with a ball, and the case being provided with a restricted socket for frictionally securing the ball in the end of the case, the brush being normally housed within the case, and when it is desired to use the brush, it being simply necessary to give the case a quick jerk to snap the ball forwardly into the socket.

A further object of the invention is to provide a case for the brush which will be ventilated so that the brush, when housed within the case, with the ball seated at the bottom thereof, will be thoroughly ventilated and maintained in a sanitary condition.

A further object is to provide the case at one end with a container for soap and at the opposite end with a dispenser for cream, the plunger of the dispenser being hollow and forming a cap for the socket end of the case, and also serving as a housing for a double suction cup for attaching a mirror, with which the plunger is provided, to a suitable support within the line of vision of the shaver.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification:

Figure 1 is a longitudinal sectional view through a shaving kit embodying my improvements and showing the brush housed in the case,

Fig. 2 is a longitudinal sectional view showing the brush in operative position on the case, which forms a handle for the brush, and

Fig. 3 is a side elevation of a modified form of case for the brush.

Referring now to the drawings in which like characters of reference designate similar parts in the various views, 10 designates a case 50 which is substantially cylindrical in contour

and is provided in the wall with ventilating openings 11. The bottom of the case is closed by a plug 12, while the top of the case is open and is constricted to provide a beveled socket 13.

The shaving brush component comprises bristles 14 which are fixed in any preferred manner at the base ends to a ball 15. The ball is of less diameter than the diameter of the case so that the brush may be initially assembled in the case by removal of the plug 12. The brush is normally housed in the case, as best shown in Fig. 1, with the ball bearing against the plug 12. To place the brush in operative position to project beyond the open end of the case, it is simply necessary to give the case a quick downward jerk, similar to snapping a whip, whereupon the ball is hurled forward and held frictionally in the tapered socket 13, as best shown in Fig. 2. To house the brush, it is simply necessary to grasp the case in one hand and tap the bottom 12 thereof sharply against the palm of the other hand, whereupon the ball will be dislodged from the socket and will gravitate to the bottom of the case and withdraw the bristles into housed position within the case.

The socket end of the case is equipped with a shaving cream dispenser comprising a magazine 16 which is perforated at the top, as shown at 17, to permit the escape of the shaving cream 18. A hollow plunger 19 is provided with a few exterior threads 20 which engage similar threads 21 formed on the inner wall of the magazine and permit of the plunger being threaded into the magazine to compress the cream ahead of it and eject a sufficient supply for a single shave through the opening 17.

The hollow plunger 13 is preferably removably secured to the case by means of a slip joint 22, although the plunger may be threaded onto the case if desired. In addition to performing its function as a plunger, the plunger also constitutes a closure for the socket end of the case, and, furthermore, it is of sufficient interior dimensions to adequately house a double suction cup 23.

The inner wall of the plunger is equipped with a mirror 24. One of the cups of the

95

100

double suction cup may be stuck onto the side of the plunger and the other cap may be stuck onto a wall or suitable support to hold the mirror within the range of vision of the shaver.

5. A hard soap container 25 is removably secured to the plug bottom 12 of the case, preferably by means of a slip joint 26, although it may be threaded on the plug if desired.
10. The container is equipped in the end wall with a mirror 27. A supply of shaving soap 28 is concealed within the container for use in lieu of the shaving cream, if the shaver so prefers.

15. In order to accelerate the action of the ball, preferably a weight 29, formed of lead, may be poured into a recess 30 in the ball diametrically opposite the bristle securing portion thereof. When the shaving brush is detached from the case after removal of the plug 12, for cleaning or other purposes, the weight 29 will counter-balance the ball 15 so that the brush will be maintained upright and thus the bristles will not come into contact with unclean articles, such as a shelf or wash bowl, on which the brush may be stood to dry.
20. 25. In Fig. 3, there is shown a modified form of case 31 which is preferably bulged centrally and tapers toward each end, both ends being open. The bottom end is closed by a threaded plug 32 and the upper end forms a tapered socket 33 which, as above described, frictionally engages the ball 34 and holds the bristles 35 of the brush in operative position.

30. The case is provided with ventilating openings 36. A cap 37 closes the socket end 33 of the case when the brush is housed therein.

35. From the above description it will be thought that the construction and operation of the invention will be easily understood without further explanation.

40. Having thus described the invention, I claim:

45. 1. A shaving kit comprising a case, one end thereof being open and restricted to provide a tapered socket, a removable plug in the opposite end of the case, a ball slidably fitted in the case, and bristles secured to the ball, 50 said ball being of less diameter than said socket and being adapted to be frictionally engaged in the socket to extend the bristles beyond the case, said ball normally bearing upon said plug and holding the bristles withdrawn within the case.

55. 2. A shaving kit comprising a case, both ends of the case being open, a removable plug closing one end of the case, the opposite end being restricted and formed in a tapered 60 socket, a removable closure for said socket, a ball slidably fitted within said case, bristles carried by the ball, said ball being frictionally engageable in said socket to hold said bristles extended from said case and being 65 adapted to bear upon said plug to hold said

bristles withdrawn within said case, and a weight carried by the ball diametrically opposite said bristles.

3. A shaving kit comprising a case, ventilating openings in the wall of the case, one end of the case being open and tapered to provide a socket, a shaving cream magazine, a hollow plunger threaded into said magazine and removably secured to the socket end of said case, a ball slidably longitudinally in the case, bristles carried by the ball, a quick jerk of said case being adapted to hurl said ball forwardly to be frictionally engaged by said socket and present said bristles exteriorly of the case after removal of said plunger, 70 said ball normally being seated on the bottom of the case and holding said bristles withdrawn within the case and plunger, and a weight carried by the ball diametrically opposite said bristles.

4. A shaving kit comprising a centrally bulged case provided with ventilating openings, a plug closing one end of said case, a cap closing the opposite end of the case, the last named end of the case constituting a 80 beveled socket, and a bristle equipped ball within the case normally bearing upon said plug and holding said bristles withdrawn within the case, said ball being adapted to be slid longitudinally of the case and lodged 85 in said tapered socket when said case is sharply reversed whereby to extend the bristles from the case.

5. A shaving kit comprising a case adapted to form a handle and having an open end, 100 a shaving brush movable longitudinally in the case and terminating opposite the open end thereof in a ball, said open end being tapered and restricted to frictionally engage said ball and retain the same in the case when 105 said case is manually given a quick jerk to impel the brush forward and extend the bristles thereof beyond the case.

In testimony whereof I affix my signature

HARRY R. PRIEST. [L.S.]
